UNITED STATES PATENT OFFICE.

EFFINGER G. HERBINE, OF READING, PENNSYLVANIA, ASSIGNOR TO THE NOLDE AND HORST COMPANY, OF READING, PENNSYLVANIA, A CORPORATION OF PENNSYLVANIA.

DESIGN FOR AN ORNAMENTED PAPER FABRIC.

Application filed April 30, 1923. Serial No. 6,013. Term of patent 14 years.

To all whom it may concern:

Be it known that I, EFFINGER G. HERBINE, a citizen of the United States, residing at Reading, in the county of Berks and State of Pennsylvania, have invented a certain new, original, and ornamental Design for an Ornamented Paper Fabric, of which the following is a specification.

The drawing shows an ornamented paper fabric embodying my new design.

What I claim is:

The ornamental design for an ornamented paper fabric as shown.

In testimony whereof I affix my signature.

EFFINGER G. HERBINE.
